UNITED STATES PATENT OFFICE.

GEORGE C. JENSEN, OF OAKLAND, CALIFORNIA.

MECHANISM FOR LOCKING LEVERS.

1,262,201.

Specification of Letters Patent. Patented Apr. 9, 1918.

Application filed November 20, 1917. Serial No. 202,921.

To all whom it may concern:

Be it known that I, GEORGE C. JENSEN, a citizen of the United States, residing at Oakland, in the county of Alameda and State of California, have invented certain new and useful Improvements in Mechanism for Locking Levers, of which the following is a specification.

In gear shifting levers for motor driven vehicles the shiftable elements of some constructions are engageable by the lower end of the lever below its pivotal point, and are selectively engaged by lateral movement of the lever; movement in a plane at right angles to that of the selective plane of movement operating the shiftable elements to control the movement thereof.

This invention relates to a locking device for preventing the operation of the before described construction and accomplishes the locking result by providing a construction which is cheap to manufacture and which may be installed at little cost.

The invention consists broadly in providing an axially rotatable lever locking bolt adapted when rotated to lie with a portion of its surface within a depression in the lower end of the lever, and actuated by the operation of a suitable plunger coöperating with which is a lock controlled mechanism, preferably of the key type.

With the above mentioned and other objects in view, the invention consists in the novel construction and combination of parts hereinafter described.

To more fully comprehend the invention, reference is directed to the accompanying drawings, wherein—

Figure 1 is a vertical sectional view of the preferred embodiment of my invention taken on line 1—1 of Fig. 3.

Fig. 2 is a vertical sectional view taken on line 2—2 of Fig. 3, viewed in the direction of the arrows.

Fig. 3 is a top plan view.

Fig. 4 is a sectional view taken on line 4—4 of Fig. 1.

In the drawings, wherein like characters of reference designate corresponding parts in the several views, 1 indicates a suitable tubular casing provided with an enlarged chamber 2 transversely of which are slidably mounted the horizontally disposed longitudinally movable shift rods 3 arranged in parallel spaced relation. Fixed to the rods 3 are the lever engaging blocks 4 pro-

vided on their adjacent faces with suitable lever receiving recesses 5.

Extending vertically through the upper open end of the tubular casing 1 is a lever 6 supported on a transverse rotatable shaft 7 extending horizontally of the casing 1, said shaft passing through a bore 8 in the lever, the walls of which taper outwardly from the center, as at 9.

A suitable securing member 10 passes through the lever and secures the same to the bolt 7, thus it will be observed that when the lever is moved or swung in a plane parallel to the longitudinal axis of the bolt 7, that the fulcrum for said lever is on the bolt 10, and when said lever is moved in a direction at right angles to the axis of rotation of the bolt, then the fulcrum point for said lever is at the point of fulcrum of the shaft 7. The lower end of the lever 6 passes downwardly between and extends below the blocks 4, being received in the recesses 5 therein, which are of sufficient depth to accommodate the full thickness of the lower end of the lever, which permits the lower end of the lever being received in said recess during the selective movement thereof.

The lever is provided at its lower end with an arcuate depression or seat 11 within which is adapted to be received a portion of a lever locking bolt 12, transversely disposed beneath the fulcrum point of the lever and rotatably mounted in bearings 13 in the lower end of the casing 1.

The bolt 12 is disposed in parallel alignment with and below the shaft 7, and is provided with a cutout 14 adapted for rotation to register with the lower end of the lever 6 and when in register therewith permitting operative movement of the lever in either its selective or operative planes.

The locking bolt 12 is formed on its end with a series of teeth 15 coöperating with corresponding teeth 16 on the lower end of the vertically disposed, longitudinally slideable, operating plunger 17, which extends upwardly through a suitable bore 18 in the wall of the housing 1.

A coiled spring 19 surrounding the lower end of the plunger 17 normally maintains the same at the upper end of its vertical movement in the bore 18, which movement rotates the locking bolt 12 to present the cutout 15 to the lower end of the lever 6. To throw the bolt 12 into locking engagement with the lower end of the lever 6,

manual downward depression on the plunger 17 is required against the action of the spring 19. When said plunger is in its depressed position, as in Fig. 2, the same is 5 automatically locked therein by any suitable locking mechanism. The conventional form illustrated consisting of a key controlled locking barrel 20 within a casing 21 and having a cam portion 22 receivable in a recess 23 in a plunger locking bolt 24. The bolt 24 is forced outwardly by a coiled spring 25 to cause the outer end 26 of the bolt to seat in a notch 27 in the side wall of the plunger 17.

10 Thus, on the rotation of the barrel 20 by the controlling key therefor, the outer end 26 of the bolt 24 will be withdrawn from the notch 27 permitting the spring 19 to automatically raise the plunger and permit 20 operative movement of the lever.

To prevent removal of the shaft 7 from its fulcrum point, the same is interlocked with the upper end of the plunger 17 by the body portion of said plunger passing 25 through a groove therein, as in Figs. 2 and 3 of the drawings.

A suitable spring member 28 having arms 29 extending one downwardly on each 30 side of the lever 6 below its fulcrum, maintain the lever in vertical position and prevent the rattling of the same.

By my improved device, I am able to engage the lower end of the lever with a suitable rotatable lever locking bolt, which 35 when in contact with the lever prevents movement of the same, and which bolt is capable of rotation to permit free movement of the lever.

Having thus described my invention, what 40 I claim as new and desire to protect by Letters Patent is:—

1. A mechanism for locking a lever fulcrumed intermediate of its length for swinging movement in two planes, comprising a 45 rotatable bolt mounted below the end surface of the lever and intersecting the path of movement of the lower end of the lever, said bolt capable of movement to position its peripheral surface into contact with the lower end surface of said lever to lock the lever from movement in either of its planes.

2. A mechanism for locking a lever fulcrumed intermediate of its length for swinging movement in two planes, comprising a 55 rotatable bolt intersecting the path of movement of the lower end of the lever and capable of rotation to throw its surface into contact with the lower end surface of said lever to lock the same from movement 60 in either of its planes, the surface of said bolt being cut or recessed to permit the free passage of the lower end surface of said lever thereover when said bolt is rotated to position said cut or recessed portion in register therewith.

3. A mechanism for locking a lever fulcrumed intermediate of its length for swinging movement in two planes, comprising a rotatable bolt mounted below the end surface of the lever and intersecting the path 70 of movement of the lower end of the lever, said bolt capable of movement to throw its peripheral surface into contact with the lower end surface of said lever to lock the lever from movement in either of its planes, 75 a longitudinal movable plunger having interengaging connection with said locking bolt and capable of manual operation to rotate said locking bolt into locking position, lock controlled means engaging said 80 plunger for retaining the same in locked position, and spring means co-operating with the plunger for operating the same to rotate said bolt to unlocked position on the release of said locking mechanism.

4. A mechanism for locking a lever fulcrumed intermediate of its length on a supporting shaft and capable of pivotal movement in two planes at right angles to each other, comprising a rotatable bolt positioned 90 parallel with said shaft and in a plane below the same and intersecting the lower end surface of said lever when the same is in a vertical position, said bolt provided with a portion for registering with the lower end 95 surface of said lever to permit operative movement of the same.

5. A mechanism for locking a lever fulcrumed intermediate of its length for swinging movement in two planes, comprising a 100 rotatable member mounted below the lower end of the lever and capable of movement to position a portion of its peripheral surface to contact with the full lower end surface of said lever to lock the lever from 105 movement in one of its planes, said lever provided with portions for extending one on either side of said locking bolt to lock the lever from movement in its other plane.

6. A lock for levers including a tubular 110 casing, a lever fulcrumed intermediate of its length on a supporting shaft carried by said casing for swinging movement in two planes, comprising a rotatable bolt capable of movement to position its surface to contact with the lower end surface of the lever to lock the same from movement in either of its planes, an operating plunger connected with said bolt to rotate the same and prevent lineal movement thereof from its supporting casing, said plunger intersecting the lever supporting shaft to lock the same from lineal movement within its supporting casing, and lock controlled means for controlling the movement of said plunger.

7. A mechanism for locking a lever, comprising a tubular casing, a lever supporting shaft extending transversely thereof and mounting a lever capable of movement therewith in one plane and of movement inde- 130

pendently thereof in another plane, a lever locking bolt disposed within said casing and parallel spaced relative with said lever supporting shaft and capable of operation to lock the lever from movement, an operating plunger arranged at right angles to said shaft and bolt and intersecting the same to prevent lineal movement of either relative to its supporting casing, said plunger adapted for operation to control said locking bolt,

and lock controlled mechanism associated with said plunger.

In testimony whereof I have signed my name to this specification in the presence of two subscribing witnesses.
